UNITED STATES PATENT OFFICE.

FRED M. HOWE, OF WELLSBORO, PENNSYLVANIA.

GAME.

Application filed April 27, 1927. Serial No. 186,988.

The present invention has reference to a game apparatus and aims to provide a game of this character which is simple and exceptionally interesting and amusing in operation.

An important object of the invention is to provide an apparatus of this character controlled solely by the element of chance to the end that the player may not, through ability or practice, regulate the movements of the balls over the game board.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a plan view of a game apparatus constructed in accordance with the invention.

Figure 2 is a vertical sectional view therethrough.

Figure 3 is a vertical sectional view through the game apparatus showing the movable member as depressed.

Referring to the drawing in detail, the device includes a circular body portion or base 5 which is formed preferably of sheet metal, however it is to be understood that the material may be varied to meet various requirements.

Within the body portion 5 is an inclined circular shelf 6 that is provided with a depending flange 7 extending downwardly where it is secured to the bottom 8 of the body portion, as clearly shown by Figure 2 of the drawing. Extending upwardly from the central portion of the bottom 8 is a pin 9 around which the spring 10 is positioned, the lower end of the spring resting on the bottom 8, the upper end of the spring contacting with the rotary member 11 which is of a diameter to fit within the central portion of the body, there being provided a flange 12 on the rotary member and depending therefrom, which flange provides means to hold the movable member against lateral movement and at the same time provide a shoulder against which the balls 13 contact as the rotary member is spinning.

This rotary member has an inclined upper

surface 14 to the end that the balls 13 will gravitate to the center thereof or to a point adjacent to the hollow stem 15 that extends from the rotary member, as shown by 60 the drawing.

The hollow stem 15 is positioned over the pin 10 and is formed with an enlargement 16 at its upper end defining a finger piece to be gripped by the fingers of the person 65 spinning the movable member.

A washer 17 is disposed between the upper end of the spring 10 and the movable member so that the movable member is normally urged upwardly.

Lines 18 are formed on the shelf 6 and divide the shelf into spaces, each space being numbered as shown by Figure 1, to the end that the balls 13, when the rotary member is spun, will come to rest opposite certain spaces, and should a player, in operating the device spin the movable member so that the balls will come to rest in the spaces 2 and 6, as shown by Figure 1, the operator has made a combined score of 8. The opponent now rotates the movable member and it is his purpose to have the balls stopped in such spaces wherein the aggregate numbers of the spaces will be more than the person's score who has previously spun the 85 movable member.

Thus it will be seen that when it is desired to operate the device, the movable member is forced downwardly against the coiled spring, whereupon the balls will roll 90 to positions adjacent to the center of the movable member. With the balls in this position, the movable member is spun by the thumb and forefinger of the person operating the movable member, and the movable member is now released.

The centrifugal force of the movable member will cause the balls to be thrown outwardly against the body portion or outer wall of the body portion and as the movable member is released and forced upwardly to a position as shown by Figure 2, the balls will continue to be moved over the shelf until the force of the movable member is finally spent and the movable member comes 105 to rest.

It is believed that in view of the foregoing detail description, the operation of the device will be apparent.

I claim:

1. A game apparatus including a body portion, an inclined shelf within the body

portion, a vertically movable spring pressed rotary member having an inclined upper surface, balls adapted to normally rest on the inclined surface, said rotary member adapted to be spun to throw the balls from the rotary member, and said shelf having lines formed on its surface dividing the shelf into spaces, and indicating characters in the spaces.

10 2. A game apparatus including a circular body portion, an inclined shelf within the body portion, a vertically movable rotary member supported within the body portion adjacent to the front edge of the shelf, balls normally supported on the vertically movable member and adapted to be thrown onto the shelf by centrifugal force, a coiled spring contacting with the bottom of the body portion and engaging the movable member to normally urge the movable member upward-

ly, and said movable member adapted to be depressed to allow the balls to roll onto the movable member.

3. A game apparatus including a circular body portion, an inclined member within the body portion, said inclined member having lines formed thereon defining spaces, a vertically movable rotary member supported within the body portion, balls resting within the body portion and adapted to move onto the vertically movable rotary member, said rotary member adapted to throw the balls onto the inclined member by centrifugal force, and said rotary member adapted to move to a position to prevent the balls from returning to the rotary member.

In testimony that I claim the foregoing as my own, I have hereto affixed my signature.

FRED M. HOWE.
